UNITED STATES PATENT OFFICE.

ADELAIDE LOUISA THOMAS, OF BRIGHTON, ENGLAND.

HOSE-SUPPORTER.

1,237,410.

Specification of Letters Patent. Patented Aug. 21, 1917.

Application filed July 17, 1914. Serial No. 851,631.

To all whom it may concern:

Be it known that I, ADELAIDE LOUISA THOMAS, a subject of the King of Great Britain, residing in Brighton, England, 5 have invented certain new and useful Improvements in Hose-Supporters, of which the following is a specification.

This invention relates to improved hose supporters of the type in which a single 10 closed loop is employed, which twice surrounds the limb, the material being crossed and one of the loops so formed embracing the hose while the other surrounds the limb.

15 The present invention has for its object to provide an improved supporter of the general type above referred to in which provision is made whereby the failure of the device owing to the displacement of the 20 material at the point of crossing is prevented.

In order that the invention may be better understood drawings are appended in which:

25 Figure 1 is a plan showing the arrangement of the parts at the point where the member forming the loops is crossed;

Fig. 2, is a view of a supporter;

30 Fig. 3, is a side view of the hose supporter in use.

Referring to the accompanying drawings, *a* indicates a body preferably formed of two lengths of wire of flat section, each of which lengths is formed into an open loop 35 and the two loops crossed to form a body of cruciform outline. The loops are soldered or otherwise secured at their point of crossing and between the limbs is passed the material *a'*, forming the support as 40 shown in Figs. 1 and 2, the material being held where it crosses by means of the cruciform body, as above described.

The reference numeral *a'* indicates the strip or band of flexible material forming 45 the limb encircling loops of the supporter, while the anchoring member which may be formed of leather or other suitable flexible fabric or material, comprises limbs *b* connected at their outer ends to a marginal

border *b'*, the material *a'* being passed under the limbs *b* and over the border as shown in the said Figs. 1 and 2. The width of the opening at the outer ends of the limbs *b* is substantially equal to the width of the material *a'* so that the material is slightly gripped at the edges.

The slide *b* forms a protective shield or guard and prevents the wire body *a* causing discomfort to the wearer.

As shown in Fig. 3, the supporter is worn so that the wire or equivalent device *a* is disposed at the back of and in the bend of the knee, the loops being located respectively one above and one below the knee, at the front.

For adjusting the length of the loops, buckles, slides, or any other similar means of adjustment *x*² may be provided.

I claim:

An anchoring member adapted for use 70 with a double loop hose supporter comprising a length of material having its ends connected together, said material being crossed upon itself to form the loops, the portions crossing one another being in contact with one another, said anchoring member having a central portion of cruciform 75 outline and a border portion to which the ends of the central portion extend, the portions of the anchoring member being disposed in a single plane, the width of the openings between the outer ends of the cruciform portion corresponding in length 80 to the width of said material, the openings coöperating in pairs, each pair comprising two opposite openings and being provided for one of said portions of material, the portions of material passing through such openings in an undulated line and being in contact with one another at the middle of 85 the anchoring member, the edges of the material being gripped between the sharp corners formed between the border and cruciform portion of the anchoring member,

and a wire body formed of two links of 90 wire crossed to form a cruciform and soldered together at their crossing, the portions of material also passing through the 95

opposite openings formed by said links, the distance between the outer length of the links corresponding to the width of the material, and the anchoring member protecting the body of the wearer from contact with the wire body.

In witness whereof I have hereunto af-

fixed my signature in the presence of the undersigned witnesses.

ADELAIDE LOUISA THOMAS.
